UNITED STATES PATENT OFFICE

JAMES HANSON, OF KIDDERMINSTER, ENGLAND

BLENDING OF WOOL, COTTON, AND OTHER FIBROUS MATERIALS

Application filed November 4, 1929. Serial No. 404,859.

This invention relates to the blending of wool, cotton and other materials.

In the manufacture of various products—for example woolen yarns—the wool from which the yarn is to be produced frequently has to consist of a blend of several different grades. The present practice is for a blender to take handfuls of the different wools and to spread them in more or less thin layers one above the other thereby producing a blended heap from which the product may subsequently be spun. This practice however has the disadvantage that the atmosphere becomes permeated with a dust from the wool which is very deleterious to health and has frequently caused anthrax and other diseases in the blender. At the same time the method does not give a perfect blend of the constituent fibres.

The primary object of the present invention is the provision of an improved apparatus for spreading these materials in layers of considerable area.

Other objects and advantages will appear hereinafter.

In order that the invention may be the more clearly understood an embodiment thereof will now be described reference being made to the accompanying drawings 30 wherein:—

Figure 1 is a vertical section on the line 1—1 of Figure 2 of the ejecting device whereby the materials are spread.

Figure 2 is a plan of the same shown partly in section.

Figure 3 is an end elevation of a modified form of conduit closure;

Figure 4 is a side view thereof with the operation of the closure means indicated in dotted lines;

Figure 5 is a side view adjacent the end of one of the conduits with a still further modified form of closure; and

Figure 6 is an end view thereof.

Referring first to Figures 1 and 2 the ejecting device comprises a single casting consisting of a hollow hub 1 carrying two conduits 2 which extend outwardly therefrom to the atmosphere. This casting is arranged with its axis vertical and the upper end of the hub

1 is open and is secured to a tubular casting 3 forming an upward continuation thereof. Said tubular casting 3 has its upper end secured through the medium of a rotatable joint as shown to the upper end of a vertical pipe section 4 forming the extremity of a pipe line extending from a receptacle for containing the materials to be blended. It will be seen that the unit constituted by the two first named castings is pneumatically continuous with said pipe line and at the same time is rotatable about a vertical axis. The conduits 2 are shaped as shown so that air passing outwardly through them will set this unit in rotation.

One of the conduits 2 may be closed or opened at will, the means for closing it being either a screw cap 5 as shown in Figure 2, or a hinged door 6 adapted to be fastened by means of a pin 7 as shown in Figure 3, or a sliding shutter 8 as shown in Figure 4, said shutter being slidable in a transverse slot in a square section boss 9 cast integral with the conduit 2.

In operation, both conduits 2 being open, the material is conveyed from the aforesaid receptacle by means of a current of air along said pipe line into the interior of said hub 1 and out through said conduits 2 to the outer atmosphere it being ejected from the rotating rotor more or less radially in a somewhat finely divided state. The wool thus falls in layers over an annular and relatively extensive area surrounding the ejector and in this way the wools of the several grades are blended. When layers have been deposited to a convenient depth, one of the conduits is closed and the process is continued with the stream passing through the other conduit only. The velocity of the air issuing from this other conduit will now be greater and the materials will therefore be ejected further from the axis of rotation. The materials will therefore be deposited on a fresh part of the floor and the total area of deposition will be increased.

What I claim and desire to secure by Letters Patent is:—

1. Apparatus for use in connection with the materials such as wool and cotton, com-

prising a hollow hub rotatable about a vertical axis a plurality of conduits extending outwardly from said hub to the atmosphere, means for conveying a stream of air bearing 5 said materials into said rotary hub and means for closing certain of said conduits at will whereby the velocity of the air issuing from the other of said conduits and therefore the distance of projection of said 10 materials, may be varied.

2. Apparatus for use in connection with the blending of materials such as wool and cotton, comprising a hollow hub rotatable about a vertical axis, a plurality of conduits 15 extending outwardly from said hub to the atmosphere and so shaped that a stream of air passing outwardly from said hub through said conduits will serve to set said conduits and hub in rotation, means for conveying a stream of air bearing said materials into said hub and means for closing certain of said conduits at will whereby the 20 velocity of the air issuing from the other of said conduits, and therefore the distance of projection of said materials, may be varied.

3. Apparatus for use in connection with the blending of materials such as wool and cotton, comprising a hollow hub rotatable about a vertical axis, two conduits extending 30 outwardly from said hub to the atmosphere and so shaped that a stream of air passing outwardly from said hub through said conduits will serve to set said conduits and hub in rotation, means for conveying a stream of air bearing said materials into said hub and means for closing one of said conduits at will whereby the velocity of the air issuing from the other conduit, and therefore the distance said materials are projected 35 40 therefrom, may be varied.

4. Apparatus for use in connection with the blending of materials such as wool and cotton fibres embodying therein a hollow hub rotatable about a vertical axis, two ar- 45 cuate conduits connected with said hub at substantially diametrically opposite points and having the axes of the discharge open- 50 ings thereof substantially tangential to said hub, and oppositely directed as to each other, means adapted for connection with a receptacle for fibers to be blended and a source of air under pressure for carrying the fibres in suspension to said hub, a closure member, and co-operating means upon one 55 of said conduits and upon said closure member, whereby said closure member may be made operative or inoperative to prevent the flow of the fibre-laden air through the conduit with which it co-operates.

60 In witness whereof I affix my signature.
JAMES HANSON.
